UNITED STATES PATENT OFFICE.

WILLIAM F. HOLEKA, OF SAN FRANCISCO, CALIFORNIA.

DESIGN FOR A RADIATOR-CAP ORNAMENT.

Application filed May 2, 1925. Serial No. 13,305. Term of patent 3½ years.

To all whom it may concern:

Be it known that I, WILLIAM F. HOLEKA, a citizen of the Czechoslovak Republic, residing at San Francisco, in the county of San Francisco and State of California, have invented a new, original, and ornamental Design for a Radiator-Cap Ornament, of which the following is a specification, refer-

ence being had to the accompanying drawing, forming a part thereof.

Figure 1 is a front elevation, and,

Figure 2 is an end view.

I claim:

The ornamental design for a radiator cap ornament, as shown.

WILLIAM F. HOLEKA.
